UNITED STATES PATENT OFFICE.

FRANK N. REEVES, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 4, 1919. Serial No. 342,441.

To all whom it may concern:

Be it known that I, FRANK N. REEVES, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone exchange systems and particularly to those 10 systems in which machine switching apparatus is used for extending and completing talking connections.

In telephone systems of the character in 15 which register senders are employed for controlling the selective movement of the automatic switches, it is the customary practice to position the registers either by means of a condition set up in response to 20 the operation of the keys on an operator's keyboard, or by means of current impulses sent from the transmitter at the calling substation or operator's position. The registers in this manner are caused to take positions representing a desired designation, 25 and thereafter serve to control the selective operation of the switches to establish the desired connection.

It is the object of this invention to provide 30 in systems of the above general character, means comprising a variably operable mechanism, responsive to series of current impulses, for positioning the registers of the sender in accordance with said impulse series to record on said registers the required designations.

Accordingly, one feature of the invention has to do with the provision of means comprising a plurality of electro-mechanisms arranged 40 to be successively operated in variable numbers in response to series of current impulses for positioning the sender registers.

Another feature relates to the provision 45 of a series of relays, successively responsive in variable numbers to series of current impulses and arranged to be successively associated with the sender registers for positioning these registers in accordance with 50 the digits of wanted numbers.

A still further feature of the invention resides in the provision of a plurality of series of relays, each series successively operable in response to current impulses, and 55 arranged to be associated in alternate suc-

cession with the several registers of the sender for the purpose of positioning these registers in correspondence with the digits represented by said impulses.

Other and further advantages derived 60 from the present invention will sufficiently appear from a consideration of the following description and appended claims.

In the drawings which form a part of this application, Figs. 1, 2, 3 and 4, when taken 65 with Fig. 2 to the right of Fig. 1, Fig. 3 below Fig. 1, and Fig. 4 to the right of Fig. 3, illustrate so much of a telephone system as is necessary to an understanding of the invention. Fig. 1 shows a subscriber's line, 70 a group selector switch, a line switch for extending the subscriber's line to idle group selectors and a sender selector. Fig. 2 shows the circuits of a final selector switch. Fig. 3 illustrates a plurality of electro- 75 mechanisms for variably positioning the switch controlling registers of the sender. This figure also shows the usual counting relay set for controlling the movement of the selective switches in accordance with the 80 setting of the sender registers. Fig. 4 shows the switch controlling registers.

The selective switches, shown in Figs. 1 and 2, may be of the type described in Patent No. 1, 123,696, issued to Craft and 85 Reynolds January 5, 1915. For simplicity in the description of the present invention, the group selector switch is assumed to be provided with ten sets of brushes, each having access to a group of trunks leading to 90 final selectors. Likewise, the final selector switches are provided with ten sets of brushes, each set serving ten groups of subscribers' lines each group comprising ten lines. By thus arranging the grouping of 95 trunks and lines on a decimal basis, the necessity of translation is obviated. It is to be understood, however, that the invention is equally well adapted to systems in which translation is involved, the omission 100 of this feature being merely to simplify the description of the operation.

The sequence switches, which are used for making the necessary circuit changes in this disclosure, may be of the construction 105 shown in the patent to Reynolds and Baldwin, No. 1,127,808, issued February 9, 1915. Where but one of these sequence switches occurs on a sheet of drawings, it is obvious that all contacts appearing on the same 110

sheet are controlled by such sequence switch. In Fig. 4, however, where four sequence switch registers are shown, the contacts, enclosed within the rectangles set off by broken lines, are controlled by the respective sequence switches located within these rectangles.

According to the present invention each of the switch controlling senders is provided with two sets of counting relays. These sets of relays are arranged to be energized in variable numbers in response to series of impulses transmitted from a calling subscriber's substation or from an operator's position. After the counting relays of the set have been operated in accordance with the number of impulses transmitted, they then become effective to determine the positioning of the sender registers. Inasmuch as the invention is particularly applicable to full automatic systems, it is shown in the present disclosure as embodied in a system of that character. It will be obvious, however, from a consideration of the following description, that in systems where operators take part in the establishment of connections, impulse transmitters may be provided at the operators' positions for controlling the setting of the sender registers.

In the detailed description of the operation of the system, which will now be given, it is assumed that the subscriber at the substation 100 desires to obtain a telephone connection with the substation 200, the number of which line is 1012. Upon removing his receiver from the switchhook, the calling subscriber at substation 100 closes the line circuit to cause the energization of the line relay 102. Relay 102, attracting its armature, closes a circuit as follows for the stepping magnet 104 of the line switch: Battery, through the armature and contact and winding of stepping magnet 104 to ground at the front contact and armature of relay 102. Stepping magnet 104 interrupts its own circuit and advances the brushes 105, 106 and 107 over the terminals of trunks leading to group selector switches. As soon as the test brush 107 engages the terminal 110 of a trunk line leading to an idle group selector, a circuit is established from battery through the winding of cutoff relay 103, brush 107, terminal 110, winding of relay 111, contact 113 (1) of sequence switch 120 to ground. Cutoff relay 103 opens the circuit of relay 102, which, by releasing its armature, interrupts the circuit of the stepping magnet 104, causing the line switch to come to rest on the terminals of the idle trunk. Relay 111 becomes energized at the same time and completes a circuit from ground through its armature and contact, winding of sequence switch 120 to battery and ground. Sequence switch 120 moves out of position 1. On

leaving position 1 sequence switch 120 opens the circuit of relay 111 so that said sequence switch stops in position 2. The cutoff relay 103 is maintained energized by means of a substitute circuit including sequence switch 70 contact 112 and resistance 152.

In position 2 of sequence switch 120 the sender selector, whose brushes are shown at 119, 121, 122, 123, 124 and 125, is set in operation to find an idle register sender 75 and associate the same with the circuits of the group selector switch. The circuit for the stepping magnet 117, which operates the brushes of the sender selector, may be traced from battery through the winding of said 80 magnet, armature and contact thereof, contact 118 (2) to ground at the contact and left-hand armature of relay 116. The brushes of the sender selector advance step-by-step until an idle sender is reached, at 85 which time a circuit is closed from battery through the winding of relay 116, brush 119, conductor 153, contact 302 (1) of sequence switch 300, winding of relay 319 to ground. Relay 116 energizes and opens at its left-hand armature the circuit for stepping magnet 117. The brushes 119, 121, 122, 123, 124 and 125, therefore, stop on the terminals corresponding to an idle register sender. Relay 116 at its right-hand armature completes a circuit including contact 115 (2) for driving sequence switch 120 out of position 2 and into position 3. The relay 319, which energizes in series with relay 116, closes a circuit from ground 100 through its armature and contact, contact 301 (1), winding of sequence switch 300 to battery and ground. The closure of this circuit causes the sequence switch 300 to advance from position 1 into position 2. 105

As soon as the sender selector has found an idle sender, a circuit is established from battery through the left-hand winding of stepping relay 303, conductor 154, brush 122, contact 126 (3), terminal 108, brush 105 over the loop of the calling line, brush 106, terminal 109, contact 127 (3), brush 121, conductor 155, right-hand winding of relay 303 to ground. This circuit, which includes the calling subscriber's substation in series therewith, comprises the impulse circuit over which series of impulses are sent by the calling subscriber's transmitter 101 to cause the positioning of the sequence switch registers. For the first series of 110 impulses which represents the first digit of the called number, the first set of counting relays, shown at the top of Fig. 3, is associated with the stepping relay 303. Relay 303 by attracting its right-hand armature closes an energizing circuit for the slow-to-release relay 304. Relay 304 completes a circuit from ground through its right-hand armature and contact, switch arm 310, conductor 331, contact and right- 115 120 125 130

hand armature of relay 401, winding of thousands register 400 to battery and ground. The register 400, energizing in this circuit, leaves the position in which it happens to be resting and commences to rotate.

The switch arm 310, over which the above traced circuit is established, is one of a plurality of switch arms comprising a steering switch, whose function it is to alternately associate the stepping relay 303 first with one and then with the other of the sets of counting relays. The steering switch arms 307, 308, 309, 310, 311 and 312 are controlled by means of the stepping magnet 313, which is arranged to advance said arms on its deenergization.

The calling subscriber now manipulates his transmitter 101 to send one impulse corresponding to the first digit of the desired number. The interruption of the impulse circuit causes the release of the stepping relay 303. Relay 303 closes a circuit from ground over its left-hand armature and contact, contact and left-hand armature of relay 304, winding of slow-to-release relay 305, steering switch arm 307 (first position), conductor 332, left-hand armature and back contact of the No. 1' relay 334 of the first counting relay set, winding of the No. 1 relay 335, contact and left-hand armature of relay 320 to battery and ground. The No. 1 counting relay 335 energizes in this circuit and prepares a circuit for the No. 1' counting relay 334 in series therewith by the closure of its left-hand armature and contact. The No. 1' relay 334, however, does not energize at this time since it is shunted by the direct path to ground at the left-hand armature and back contact of the stepping relay 303. The slow-to-release relay 305 energizes and closes a circuit from ground through its armature and contact, winding of the stepping magnet 313 to battery and ground.

The stepping magnet 313 energizes preparatory to advancing the switch arms into the second position. Upon the closure of the impulse circuit at the termination of the first impulse, the stepping relay 303 becomes energized and opens the above traced circuit for the No. 1 counting relay 335. This removes the shunt from around the No. 1' counting relay 334 and these relays energize and lock up in the following circuit: Battery, left-hand armature and contact of relay 320 through the windings of the No. 1 and No. 1' relays 335 and 334 in series, left-hand armature and contact of relay 335 to ground. The slow-to-release relays 304 and 305 do not retract their armatures due to the brief energization and deenergization of the stepping relay 303 that take place during the transmission of a series of impulses from the subscriber's transmitter.

While, however, the calling subscriber is re-

setting the transmitter 101 after having sent the first digit, the stepping relay 303 maintains its armatures attracted for a period sufficient to permit the deenergization of the slow-to-release relay 305. The circuit of the stepping magnet 313 is thus opened and the steering switch advances into its second position. The above traced circuit for the energization of the thousands register 400 is opened at the switch arm 310, but a substitute circuit is prepared for the operation of said register by the switch arm 311 in its second position. The register 400, therefore, continues to rotate until it reaches position 1 which corresponds to the number of impulses sent by the calling subscriber in accordance with the first digit. In position 1 of the register 400 a circuit is established from battery through the winding of relay 401, contact 403 (1), conductor 333, contact and right-hand armature of the No. 1' counting relay 334, back contacts and right-hand armatures of the No. 2', No. 3', No. 4' relays and so forth to ground at the back contact and right-hand armature of the No. 0' relay 376. Relay 401 energizes and opens the circuit of the register 400 permitting said register to stop in position 1. Relay 401 closes a circuit from battery through its winding and contact and left-hand armature, winding of relay 402, conductor 336, switch arm 309 (position 2) to ground. With the register 400 in position 1 and with relay 402 energized in series with relay 401, a circuit is completed from battery through the winding of relay 320, conductor 337, left-hand armature and contact of relay 402, contact 404 (1), conductor 338, contact and right-hand armature of relay 335, back contacts and right-hand armatures of all the lower counting relays succeeding relay 335, conductor 339, switch arm 308 (position 2) to ground. Relay 320 becomes energized in this circuit and locks up in a circuit from battery through its windings and contact and right-hand armature to ground at switch arm 308. The attraction of the left-hand armature of relay 320 opens the above traced locking circuit for the counting relays whereupon relays 335 and 334 are released. It will be observed from the above description that the register 400 stops in a position corresponding to the digit sent by the calling subscriber and cannot stop in any other position since the circuit is not completed for the stop relay 401 until said register has reached a position corresponding to the number of pairs of counting relays that are energized and locked up.

As above noted, the steering switch advanced from position 1 into position 2 at the termination of the first series of impulses. This operation of the steering switch disassociates the stepping relay 303 from

the first set of counting relays and associates such relay with the second set of counting relays preparatory to setting the hundreds register 410. As the steering switch reached position 2 a circuit was completed from ground through the contact and right-hand armature of relay 304, switch arm 310 (position 2), conductor 340, contact and right-hand armature of relay 411, 5 winding of the hundreds register 410 to battery and ground. The register 410 leaves the position in which it is standing and begins to rotate. The calling subscriber now operates his dial 101 to send ten impulses 10 representing the second digit of the wanted number. The stepping relay 303 deenergizes at the first interruption of the impulse circuit and completes a circuit from ground through its left-hand armature and contact, contact and left-hand armatures of 15 relay 304, winding of relay 305, switch arm 307 (position 2), conductor 341, left-hand armature and back contact of the No. 1' counting relay 342, winding of the No. 1 counting relay 343, contact and left-hand armature of relay 330 to battery and ground. Relay 343 becomes energized and prepares a circuit at its left-hand armature and contact for the energization of relay 20 25 30 35 40 45 50 55 60 65 70 75 80 85 90 95 100 105 110 115 120 125 130

342. Relay 342, however, is shunted out by the direct path to ground at the back contact and left-hand armature of relay 303. Relay 305 energizes in series with relay 343 and closes a circuit for the energization of the stepping magnet 313. As soon as the impulse circuit is closed at the termination of the first impulse, relay 303 attracts its armatures and removes the shunt from around the No. 1' counting relay 342. Relays 343 and 342 are now energized and locked up in a circuit from battery through the left-hand armature of relay 330, windings of relay 343 and 342 in series, left-hand armature and contact of relay 343 to ground. At the second interruption of the impulse circuit, relay 303 releases its armatures and closes a circuit from ground over its left-hand armature and contact, contact and left-hand armature of relay 304, winding of relay 305, switch arm 307 (position 2), conductor 341, left-hand armature and front contact of relay 342, left-hand armature and back contact of the No. 2' relay 344, winding of the No. 2 counting relay 345, contact and left-hand armature of relay 330 to battery and ground. Relay 345 attracts its armatures and upon the next closure of the impulse circuit the shunt is removed from around relay 344, permitting relays 345 and 344 to energize and lock up in the manner already described. This procedure continues, a pair of counting relays being energized and locked up for each impulse, until the last impulse of the series is sent, at which time the 0 and 0' relays 346

and 347 are energized. At the termination of the second series of impulses the slow to release relay 305 deenergizes and opens the circuit of the stepping magnet 313. This permits the advance of the steering switch 70 into its third position.

On leaving position 2 the switch arm 308 opens the holding circuit of relay 320 causing this relay to become deenergized. Likewise, the switch arm 309 on passing out of position 2 severs the holding circuit of relays 401 and 402. In position 3, switch arm 311 closes a substitute circuit to maintain the energization of the hundreds register 410, the original energizing circuit of which 80 has been opened as switch arm 310 leaves position 2. The hundreds register 410 rotates until it reaches position 0 which corresponds to the second digit of the called number. In this position a circuit is closed from battery through the winding of relay 411, contact 413 (0), conductor 348, front contact and right-hand armature of the 0' relay 347 to ground. Relay 411 attracts its armatures and opens the operating circuit of register 410. Register 410, therefore, ceases to rotate. Relay 411 completes a circuit from battery through its winding and contact and left-hand armature, winding of relay 412, conductor 349, switch arm 309 (position 3) to ground. With the register 410 in position 0 and relay 412 energized, a circuit is established from battery through the winding of relay 330, conductor 350, armature and contact of relay 412, contact 414 (0), conductor 351, front contact and right-hand armature of relay 346, conductor 352, switch arm 308 (position 3) to ground. Relay 330 becomes energized in this circuit and opens the locking circuit of the counting relays, whereby these relays are restored to their normal positions. Relay 330 at its right-hand armature closes a locking circuit for itself including switch arm 308 in position 3.

The steering switch having been advanced into its third position following the transmission of the second series of impulses, stepping relay 303 is now associated with the first set of counting relays ready to control the positioning of the tens register 420. As the steering switch is advanced into position 3 a circuit is established from ground through the contact and right-hand armature of relay 304, switch arm 310 (position 3), conductor 353, contact and right-hand armature of relay 421, winding of register 420 to battery and ground. Register 420 energizes in this circuit and commences to rotate. The calling subscriber manipulates his dial 101 in accordance with the third digit 1 to send a single impulse. Relay 303 deenergizes in response to the interruption of the line circuit and closes a circuit from ground

through its left-hand armature and contact, contact and left-hand armature of relay 304, winding of relay 305, switch arm 307 (position 3), conductor 332, left-hand armature 5 and back contact of the No. 1' relay 334, winding of the No. 1 relay 335, contact and left-hand armature of relay 320 to battery and ground. Upon the closure of the impulse circuit the No. 1' relay 334 energizes 10 and locks up in series with the No. 1 relay. In the manner above described, the tens register 420 is caused to stop in position 1 and relay 421 is energized. At the termination of the third series of impulses 15 relay 305 releases its armature and opens the energizing circuit of the stepping magnet 313. Magnet 313 consequently advances the steering switch into position 4. On leaving position 3, the switch arm 308 opens the circuit of relay 330, and switch arm 309 20 opens the circuit of relays 411 and 412.

In position 4 of the steering switch relay 320 is locked up in a circuit including switch arm 308, and relays 421 and 422 are 25 locked up in a circuit including switch arm 309. In position 4 of the steering switch a circuit is established from ground through the contact and right-hand armature of relay 304, switch arm 310 (position 4), conductor 355, contact and right-hand armature of relay 431, winding of the units register 430 to battery and ground. The register 430 energizes and commences to rotate. 30 The calling subscriber operates the transmitter 101 to send two impulses in accordance with the final digit of the called number. At the first interruption of the line relay 303 releases its armature and closes a circuit from ground through its left-hand 35 armature and contact, contact and left-hand armature of relay 304, winding of relay 305, switch arm 309 (position 4), left-hand armature and back contact of the No. 1' counting relay 342, winding of relay 343, 40 contact and left-hand armature of relay 330 to battery and ground. Relay 343 energizes and prepares a circuit for relay 342. When the impulse circuit is again closed 45 relay 303 energizes and removes the shunt from around relay 342 so that relays 343 and 342 energize and lock up in series with each other. In response to the next and final impulse of the series the second pair 50 of counting relays are energized. After the lapse of the required interval following the transmission of the final series of impulses 55 the relay 305 releases its armature and opens the energizing circuit of the stepping magnet 313. The steering switch is thereupon advanced from position 4 into position 5. On leaving position 4 the circuit of relay 320 is opened at switch arm 308 and the circuit of relays 421 and 422 is opened at switch arm 309. As soon as the units register 430 reaches position 2, a circuit is completed from battery through the winding of relay 431, contact 435 (2), conductor 356, front contact and right-hand armature of relay 344, back contacts and right-hand armatures of all the upper counting relays 70 succeeding relay 344, to ground at the back contact and right-hand armature of relay 347. Relay 341 energizes and opens the circuit of register 430, causing this register to come to rest. Relay 431 also closes a 75 circuit from battery through its winding and contact and left-hand armature, winding of relay 432, conductor 357, switch arm 309 (position 5) to ground. With the register 430 in position 2 and relay 432 energized a circuit is closed from battery through the winding of relay 330, conductor 350, left-hand armature and contact of relay 432, contact 436 (2), conductor 358, front contact and right-hand armature of 80 relay 345, back contacts and right-hand armatures of all the lower counting relays succeeding relay 345, conductor 352, switch arm 308 (position 5) to ground. Relay 432 closes a circuit from ground through its 85 right-hand armature and upper contact, conductor 359, switch arm 312 (position 5), contact and armature and winding of magnet 313 to battery and ground. Magnet 313 energizes and, interrupting its own circuit, causes the advance of the side switch into its normal position. In leaving position 5 the circuit of relay 330 is opened at switch arm 308 and the circuit of relays 431 and 432 is opened at switch arm 309. 90

After the units register has been positioned and when relay 432 attracts its armatures a circuit is established from ground through the right-hand armature and lower contact of relay 432, conductor 360, contact 301 (2), winding of sequence switch 300 to battery and ground. Sequence switch 300 thereupon moves out of position 2 and into position 3. The fundamental circuit is now completed for controlling the operation of 100 the group selector, shown in Fig. 1, in its brush selecting movement. This circuit may be traced from battery through the winding of relay 139, contact 134 (3), brush 123, conductor 156, winding of the stepping relay 318, outer armature and contact of the No. 1' counting relay 361, contact 314 (3), conductor 157, brush 124, contact 132 (3) to ground. Relay 139 energizes and completes 105 a holding circuit for itself over its contact 301 (2), winding of sequence switch 300 to battery and ground. Sequence switch 300 moves out of position 3 and into position 4. The fundamental circuit is now completed for controlling the operation of 110 the group selector, shown in Fig. 1, in its brush selecting movement. This circuit may be traced from battery through the winding of relay 139, contact 134 (3), brush 123, conductor 156, winding of the stepping relay 318, outer armature and contact of the No. 1' counting relay 361, contact 314 (3), conductor 157, brush 124, contact 132 (3) to ground. Relay 139 energizes and completes 115 a holding circuit for itself over its contact 301 (2), winding of sequence switch 300 to battery and ground. Sequence switch 300 moves out of position 3 and into position 4. The fundamental circuit is now completed for controlling the operation of 120 the group selector, shown in Fig. 1, in its brush selecting movement. This circuit may be traced from battery through the winding of relay 139, contact 134 (3), brush 123, conductor 156, winding of the stepping relay 318, outer armature and contact of the No. 1' counting relay 361, contact 314 (3), conductor 157, brush 124, contact 132 (3) to ground. Relay 139 energizes and completes 125 a holding circuit for itself over its contact 301 (2), winding of sequence switch 300 to battery and ground. Sequence switch 300 moves out of position 3 and into position 4. In position 4 of sequence switch 300 the up-drive power magnet 142 is energized in a circuit including contact 140 (4) and the 130

front contact and right-hand armature of relay 139. The magnet 142 causes the brush shaft 157 to be moved upward by the power drum 158. The stepping relay 318, which 5 also energizes in the fundamental circuit, closes a circuit from ground through its armature and contact, contact 316 (3), conductor 362, contact 405 (1), conductor 363, winding of relay 364 to battery and ground. 10 Relay 364 attracts its armature and prepares a circuit for relay 361 in series therewith. Relay 361, however, does not energize since it is short-circuited by the ground at the armature and front contact of relay 318. 15 When the brush shaft 157 of the group selector advances the brush 144 into engagement with the first metallic segment of the commutator 159, the following circuit is closed for relay 139: Battery through the 20 winding and contact and left-hand armature of said relay, contact 133 (4), commutator 159, brush 144 to ground. This direct circuit to ground shunts the stepping relay 318 in the well-known manner. Relay 318 releases its armature and removes the shunt from around the No. 1' counting relay 361. Relays 364 and 361 are thereupon energized in a circuit from battery through the windings of said relays, contact and armature of 25 relay 364, contact 317 (3) to ground. Relay 361 at its inner armature closes a circuit including contact 315 (3) for driving sequence switch 300 out of position 3 and into position 5. In passing from position 3 to 30 position 5 the sequence switch contact 317 is opened to permit the deenergization of the counting relays. The relay 361 upon energizing opens the fundamental circuit at its outer armature. The relay 139, however, remains energized until the brush 124 reaches 35 the next insulating section of the commutator 159. Relay 139 then releases its armatures and a circuit is completed from ground over the right-hand armature and back contact of relay 139, contact 135 (4), winding of sequence switch 120 to battery and ground. Sequence switch 120 energizes and advances into position 5. 40 With sequence switch 120 in position 5 a circuit is established from battery through the winding of relay 139, contact 134 (5), contact 138 (5) to ground. Relay 139 energizes and completes a circuit from ground over its right-hand armature and front contact, contact 140 (5), through the winding of sequence switch 120 to battery and ground. Sequence switch 120 advances into position 6. In this position the updrive power magnet 219 of the final selector is energized 45 and causes the brush shaft 157 to advance the selected set of brushes over the terminals of the trunk group to search for a trunk leading to an idle final selector. The selected set of brushes are tripped so as to make engagement with the trunk terminals by means of 50 a trip magnet 141 which is energized in a circuit including sequence switch contact 136 (5 to 6). If the first trunk in the group is busy a ground will be present on the test terminal thereof, and relay 139 is maintained 55 energized in position 6 of sequence switch 120 by means of the following circuit: Battery through the winding or relay 139, contact and left-hand armature of said relay, contact 134 (6), brush 147, test terminal 150 and thence to ground over the test brush and contact 161 at some other group selector. As soon as an idle trunk is reached the relay 139 deenergizes and closes a circuit from 60 ground through its right-hand armature and back contact, contact 135 (6), winding of sequence switch 120 to battery and ground. Sequence switch 120 advances into position 8. A ground is placed upon the test terminal 150 of the selected trunk by the closure of 65 contact 161 in positions 7 to 18 to prevent the seizure of this trunk by other switches. The fundamental circuit is now extended through to the final selector switch and may be traced from battery through the winding of relay 206, contact 207 (1), contact 202 (1), terminal 149, brush 146, contact 130 (8), brush 124, conductor 157, contact 314 (5), contact and outer armature of relay 361, winding of relay 318, conductor 156, 70 brush 123, contact 129 (8), brush 145, terminal 148, contact 201 (1) to ground. Relay 206 becomes energized and completes a circuit from ground through its right-hand armature and front contact, contact 205 (1), winding of relay 203 to battery and ground. Relay 203 is energized and locks up in a circuit from battery through the winding and contact and left-hand armature of said 75 relay, terminal 150, brush 147 to ground at 80 sequence switch contact 161. The relay 203 also closes a circuit from ground through its right-hand armature and front contact, contact 204 (1), winding of sequence switch 220 to battery and ground. The sequence switch 220 advances from position 1 to position 2. In this position the updrive power magnet 219 of the final selector is energized 85 in a circuit from battery, through the winding of said magnet, contact 214 (2) to 90 ground at the contact and left-hand armature of relay 206. The brush shaft of the final selector is moved upward in the brush selecting operation. The stepping relay 318 also energizes in the fundamental circuit 95 and closes a circuit from ground through its armature and contact, contact 316 (5), conductor 365, contact 415 (0), conductor 366, armature and back contact of the No. 0' counting relay 367, winding of the zero 100 counting relay 368 to battery and ground. Relay 368 energizes in this circuit and prepares a circuit for relay 367. In the upward movement of the final selector brush shaft the brush 223 makes engagement with 105

the first metallic segment of the commutator 230. A circuit is then closed from battery through the winding of relay 206, contact 207 (2), contact 208 (2), commutator 230, 5 brush 223 to ground. This circuit shunts the stepping relay 318, which, by deenergizing, removes the shunt from around the relay 367, permitting relays 368 and 367 to energize and lock up in a circuit closed to 10 ground at contact 317 (5). As the brush 223 moves onto the next insulating segment of the commutator the stepping relay 318 is energized and the No. 9 counting relay 369 is energized. In this manner the movement 15 of the final selector continues until it has reached its tenth brush tripping position, at which time all of the counting relays will have been energized. The energization of the No. 1' counting relay 361 causes the sequence switch 300 to be advanced from position 5 to position 7. In moving from position 5 to position 7 contact 317 opens and causes the release of all the energized counting relays. When the 20 brush 223 reaches the next insulating segment following the opening of the fundamental circuit by relay 361, the relay 206 deenergizes and completes a circuit from ground over its right-hand armature and 25 back contact, contact 209 (2), winding of sequence switch 220 to battery and ground. Sequence switch 220 advances into position 3. In this position the trip magnet 218 is energized in a circuit closed at contact 216 so that on the next upward movement of 30 the brush shaft the selected set of brushes are tripped into engagement with the line terminals.

In position 3 of sequence switch 220 and 40 position 7 of sequence switch 300, the fundamental circuit is again closed to control the group selecting movement of the switch. Relay 206 by energizing closes a circuit from ground through its right-hand armature and front contact, contact 209 (3), winding of sequence switch 220 to battery and ground. This sequence switch moves from position 3 into position 4. In position 4 the updrive power magnet 219 is 45 energized by means of a circuit closed at contact 214 and the brush shaft is caused to advance. The stepping relay 318 by energizing closes a circuit from ground over its armature and contact, contact 316 (7), conductor 370, contact 423 (1), conductor 363, winding of relay 364 to battery and ground. On reaching the first metallic segment of 50 the commutator 230, corresponding to the first group of ten lines, the brush 223 causes the relay 318 to be short circuited in the manner well understood. On reaching the next insulating portion of the commutator the brush 223 permits the deenergization of relay 206. Relay 206 closes a circuit from 55 ground through its right-hand armature

and back contact, contact 209 (4), winding of sequence switch 220 to battery and ground. Sequence switch 220 moves out of position 4 and into position 5. Relay 361, which was energized upon the deenergization of relay 318, closes a circuit including contact 315 (7) for driving sequence switch 300 into position 9.

The fundamental circuit is now closed for the final or units selection and relays 206 75 and 318 become energized. Relay 206 closes a circuit from ground through its right-hand armature and front contact, and contact 209 (5) for moving sequence switch 220 into position 6. In this position the updrive 80 magnet 219 is again energized and the selected set of brushes 224, 225 and 226 are advanced over the group of ten terminals containing the terminals of the called line. Relay 318 by energizing closes a circuit from ground through its armature and contact, contact 316 (9), conductor 372, contact 437 (2), conductor 373, armature and back contact of relay 374 winding of relay 375 to battery and ground. In the manner 85 already described the proper number of counting relays are energized, after which the fundamental circuit is opened at the sender and sequence switch 300 advances from position 9 into position 1. When the brush 222 reaches the next insulating segment of commutator 231 after the fundamental circuit has 90 been severed at the sender, the local circuit for relay 206, which includes contacts 207 and 208, is opened. Relay 206 deenergizes and closes a circuit from ground through its right-hand armature and back contact, contact 209 (6), winding of sequence switch 220 to battery and ground. Sequence switch 220 advances into position 8.

When the sender sequence switch 300 reaches position 10 after the final or units selection has been completed, a circuit is established from ground through the contact 306 (10 to 18), conductor 162, brush 125, contact 137 (8), winding of sequence switch 120 to battery and ground. Sequence switch 120 advances into position 10 where the talking circuit is completed at contacts 129 and 130.

Upon the final selector sequence switch 220 arriving in position 8, a circuit is closed for the application of ringing current to the called line. This circuit may be traced from the ringing source 232, relay 233, contact 210 (8), brush 224, terminal 227 over the loop of the called line 200, terminal 228, brush 225 and contact 211 (8) to ground. The response of the called subscriber causes, in the well-known manner, the energization 110 of relay 233. This relay closes a circuit including contact 212 (8) for driving sequence switch 220 into position 10, which is the 115 talking position thereof.

The conversation having been completed 120 125 130

the calling subscriber replaces his receiver on the switchhook, causing the opening of the calling line circuit. This permits the supervisory relay 131 to deenergize. A circuit is then closed from ground through the armature and contact of relay 131, contact 114, closed from position 4 to position 17, winding of sequence switch 120 to battery and ground. The sequence switch 120 advances from position 10 into position 18. In position 18 of sequence switch 120 the group selector brush shaft is restored to its normal position by means of the down-drive power magnet 143. The circuit for this magnet is closed at contact 151. On reaching the normal position the brush 144 engages the contact 163, thus closing a circuit including contact 128 (18) for moving sequence switch 120 into its normal position 1. As soon as test brush 147 leaves terminal 150 the holding circuit of relay 203 is opened. Relay 203 releases its armatures and closes the following circuit: Ground right-hand armature and back contact of relay 203, contact 209 (2 to 17) winding of sequence switch 220 to battery and ground. Sequence switch 220, by means of this circuit, advances into position 18. In position 18 of sequence switch 220 the final selector brush shaft is returned to its normal position by means of the down-drive power magnet 221. The circuit for the magnet 221 is closed at contact 215 (18). On reaching the normal position a circuit is closed from ground through the brush 222, contact 234, contact 213 (18), winding of sequence switch 220 to battery and ground. Sequence switch 220 thereupon advances into its normal position 1. The switches and apparatus have thus been completely restored to their normal positions and may be taken for use in establishing subsequent connections.

What is claimed is:

- 45 1. The combination in a telephone system of selective switches for extending telephone connections, registers for controlling the selective operation of said switches, a plurality of successively operable electro-mechanisms, means responsive to current impulses for variably operating said electro-mechanisms, and means dependent on the number of said electro-mechanisms operated for positioning said registers.
- 50 2. The combination in a telephone system of selective switches for extending telephone connections, registers for controlling the selective operation of said switches, a series of electro-mechanisms, an impulse circuit, an impulse transmitter for sending impulses over said circuit, means responsive to said impulses for successively operating the electro-mechanisms of said series, and means dependent on the number of electro-mechanisms operated for determining the positioning of said registers.
- 55 3. The combination in a telephone system of subscribers' lines, a selective switch for establishing connections between said lines, means for extending one of said lines to said switch, a plurality of registers for controlling the selective movement of said switch, means for associating said registers with said line, a series of relays, means for sending impulses over said line, means responsive to such impulses for successively energizing said relays, and means controlled by said series of relays for variably setting said registers.
- 60 4. The combination in a telephone system of subscribers' lines, a selective switch for establishing connections between said lines, means for extending one of said lines to said switch, multiposition registers for controlling the selective movement of said switch, means for associating said registers with said line, a group of relays, means for sending series of impulses over said line corresponding to the digits of called numbers, means responsive to such impulses for successively energizing said relays, and means dependent upon the number of relays energized in said group for setting said registers.
- 65 5. The combination in a telephone system of selective switches for extending telephone connections, registers for controlling the selective operation of said switches, a group of electro-mechanisms, means for successively associating said registers with said group of electro-mechanisms, means responsive to current impulses for variably operating said electro-mechanisms, and means dependent on the number of said electro-mechanisms operated for positioning said registers.
- 70 6. The combination in a telephone system of selective switches for extending telephone connections, registers for controlling the selective operation of said switches, a series of relays, a circuit controlling switch for successively associating said registers with said series of relays, means for successively energizing the relays of said series, and means controlled by said series of relays for variably positioning said registers.
- 75 7. The combination in a telephone system of subscribers' lines, a selective switch for establishing connections between said lines, means for extending one of said lines to said switch, registers for controlling the selective operation of said switch, a series of relays, means for successively associating said register with said series of relays, means for sending impulses over said line, means responsive to such impulses for energizing said relays, and means controlled by said series of relays for variably setting said registers.
- 80 8. The combination in a telephone system

nisms operated for determining the positioning of said registers.

3. The combination in a telephone system of subscribers' lines, a selective switch for establishing connections between said lines, means for extending one of said lines to said switch, a plurality of registers for controlling the selective movement of said switch, means for associating said registers with said line, a series of relays, means for sending impulses over said line, means responsive to such impulses for successively energizing said relays, and means controlled by said series of relays for variably setting said registers.

4. The combination in a telephone system of subscribers' lines, a selective switch for establishing connections between said lines, means for extending one of said lines to said switch, multiposition registers for controlling the selective movement of said switch, means for associating said registers with said line, a group of relays, means for sending series of impulses over said line corresponding to the digits of called numbers, means responsive to such impulses for successively energizing said relays, and means dependent upon the number of relays energized in said group for setting said registers.

5. The combination in a telephone system of selective switches for extending telephone connections, registers for controlling the selective operation of said switches, a group of electro-mechanisms, means for successively associating said registers with said group of electro-mechanisms, means responsive to current impulses for variably operating said electro-mechanisms, and means dependent on the number of said electro-mechanisms operated for positioning said registers.

6. The combination in a telephone system of selective switches for extending telephone connections, registers for controlling the selective operation of said switches, a series of relays, a circuit controlling switch for successively associating said registers with said series of relays, means for successively energizing the relays of said series, and means controlled by said series of relays for variably positioning said registers.

7. The combination in a telephone system of subscribers' lines, a selective switch for establishing connections between said lines, means for extending one of said lines to said switch, registers for controlling the selective operation of said switch, a series of relays, means for successively associating said register with said series of relays, means for sending impulses over said line, means responsive to such impulses for energizing said relays, and means controlled by said series of relays for variably setting said registers.

8. The combination in a telephone system

- of subscribers' lines, a selective switch for establishing connections between said lines, means for extending a calling line to said switch, a plurality of registers for controlling the selective operation of said switch, a plurality of registers for successively associating said registers with said line, a group of relays, means for successively associating said registers with said group of relays, means for sending impulses over said line, means responsive to such impulses for energizing a variable number of said relays, and means controlled by said group of relays for setting said registers. 5
9. The combination in a telephone system of selective switches for extending telephone connections, a plurality of registers for controlling the selective movement of said switches, a series of relays, means for successively associating said registers with said 10 series of relays, means for successively energizing the relays of said series, means for maintaining the energization of said relays, and means dependent upon the number of relays energized for setting said registers. 20
- 25 10. The combination in a telephone system of selective switches for extending telephone connections, a plurality of registers for controlling the selective operation of said switches, a plurality of groups of electro-mechanisms, means for successively operating the electro-mechanisms of each group, and means dependent on the number of electro-mechanisms operated in said groups for variably positioning said registers. 30
- 35 11. The combination in a telephone system of selective switches for extending telephone connections, a plurality of registers for controlling the selective operation of said switches, a plurality of groups of relays, means for sending series of impulses, means responsive to such impulses for successively energizing the relays of each of said groups, and means dependent on the number of relays operated in each of said groups for variably setting said registers. 40
- 45 12. The combination in a telephone system of subscribers' lines, a selective switch for interconnecting said lines, means for extending a calling line to said switch, registers for controlling the selective movement of said switch, a plurality of groups of relays, means for sending impulses over said line, means responsive to such impulses for successively energizing a variable number of the relays of said groups, and means dependent on the number of relays of said groups that are energized for setting said registers. 55
- 50 60 13. The combination in a telephone system of selective switches for extending telephone
- connections, a plurality of registers for controlling the selective operation of said switches, a plurality of groups of relays, means for successively associating said registers with each of said groups, and means controlled by said groups of relays for variably positioning said registers. 65
14. The combination in a telephone system of selective switches for extending telephone connections, a plurality of registers for controlling the selective operation of said switch, a plurality of groups of relays, a circuit controlling switch for successively associating said registers with each of said groups, and means controlled by said groups of relays for variably positioning said registers. 70
- 75 15. The combination in a telephone system of selective switches for extending telephone connections, a series of registers for controlling the selective operation of said switches, a plurality of groups of relays, means for successively associating each of said groups of relays with alternate registers of said series of registers, and means controlled by said groups of relays for variably setting each register with which they are associated. 80
- 85 16. The combination in a telephone system of selective switches for extending telephone connections, a series of registers for controlling the selective operation of said switches, a plurality of groups of relays, means for successively associating each of said groups of relays with alternate registers of said series of registers, means for energizing a variable number of the relays in said groups, and means dependent on the number of relays energized in each group for setting the registers with which such group is associated. 90
- 95 17. The combination in a telephone system of selective switches for extending telephone connections, a series of registers for controlling the selective operation of said switches, a plurality of groups of relays, an impulse circuit, means for successively associating each of said groups of relays both with said impulse circuit and with alternate registers of said series, means for sending impulses over said circuit, means responsive to such impulses for energizing the relays of said groups, and means controlled in accordance with the number of relays energized in each group for setting the registers with which such group is associated. 105
- 110 In witness whereof, I hereunto subscribe my name this 1st day of December A. D., 1919.
- 115

FRANK N. REEVES.
